(57) **CLAIM**

The ornamental design for night glow BBQ, grill, smoker thermometer, as shown and described.

DESCRIPTION

FIG. 1 is a top angled elevational view of the temperature gauge showing my new design;

FIG. 2 is a face front plan view thereof;

FIG. 3 is a back side plan view thereof;

FIG. 4 is a right side elevational view thereof;

FIG. 5 is a left side elevational view thereof; and,

FIG. 6 is a front side elevational view thereof which is also mirrored for the back side elevational view.

My BBQ grill/smoker night glow thermometer gauge is characterized by its front segmented dial display with large pointer showing 3 cooking temperature sections, smoke, BBQ, grill and corresponding actual temperature reading along with a dial printed with the term night glow to signify the dial's ability to absorb light and transmit a glow in low or no light use. My ornamental design is also unique in its side views as shown in the drawings in its multistep raised dial mounting on a grill or smoker.
